UNITED STATES PATENT OFFICE

WILHELM BOCK, OF GWYNEDD, PENNSYLVANIA

HUMIDIFYING APPARATUS

Application filed February 11, 1929. Serial No. 338,963.

The principal object of the invention is to provide an improved humidifying apparatus for the household and other purposes. An additional object is to provide an automatically controlled humidifier, which uses the steam or water from heating radiators. Other objects relate to various features of construction and arrangement of parts, which will become apparent from a consideration of the following description and accompanying drawings wherein.

Of the drawings:

Fig. I is a vertical section of the device, showing the external casing, the valve arrangement and the controlling device;

Fig. II is a top plan view of the adjusting screw and its graduation;

Fig. III is a horizontal cross section of the hygroscopic test body and the protecting casing and

Fig. IV is partially an elevation and partially a plan view of the electric heated container.

The same reference characters indicate the same parts in all the figures.

The casing of my humidifier is composed of a lower or base member 1 and an upper member 18 and 15. The base member comprises a bottom with a recess 22, and a screw-threaded nipple 2 adapted to engage a tapped orifice in a steam or hot water radiator 23. The circular wall of the case member 1 rises from the bottom and is internally screw-threaded to engage a thread on the valve stem guide 5. This valve stem guide 5 is used as guide for the valve 4 and is provided with a conical inlet and outlet for noiseless and complete expansion of the steam. This principle is employed in the well known Laval nozzle. The valve consists of an upper stem 6, a valve disc 4 and a lower stem with a shoulder 3. A suitable spring 21 holds the valve disc 4 in closed position against the valve seat on the lower side of the valve stem guide 5. The valve 4 is made of a thermo-sensitive material and is held by its shoulder 3 in a recess 22. Under heating condition the shoulder 3 will have enough play in the recess 22, allowing the valve disc 4 to close the outlet for the steam. If the radiator con-

tains no steam the cold valve 4 will decrease its lengths so far that the valve disc 4 will be unable to close the outlet which allows the escape of undesirable air in the radiator. The upper stem of the valve 6 is provided with longitudinal recesses which give sufficient space for the outlet of the steam or the water. The valve stem guide 5 is provided with radial channels 7, through which the water will be discharged to the outer surface of the external casing. By means of cohesion and gravitation the discharged water will run downwards over the plate 27 which is in thermal relation with the radiator wall 23. The vaporized water will increase the humidity of the atmospheric air in the room. If the heat of the radiator is not sufficient to evaporize the water, it will be done by the container 28 which is electrically heated by heating elements 29. (See Fig. IV.)

The electric terminals 30, of the container 28, are connected with the electric contact points 20. This contact will be closed or opened by the prolongation 19 of the lever 8. This lever is held in position upon a fulcrum 9, by the valve 4, the spring 21, and the test body 12. The test body 12 consists of thin strips of hygroscopic material, preferably leather strips which are separated by spacing plates 13. (Fig. I.) This arrangement provides a very sensitive test body, for the control of the humidity of the atmospheric air. The lower part of the test body 12 is held by a clamp 11, which is connected by the pivot 10 to the lever 8. The lever 8 is fulcrumed on a pivot 9. The upper part of the test body 12 is held by another clamp 14. An adjusting screw 24 which engages the clamp 14 by a shoulder is inserted in a screw-threaded hole 16 in the upper member 15 of the casing. The adjusting screw 24 has a stop 25 limited by a pointer 17. This arrangement allows one turn only for the adjusting screw 24. The top part of the screw 24 is provided with a graduation 26 for direct adjustment of the percentage of relative humidity desirable in the atmospheric air. As shown, the test body 12 is protected from heat radiation of the radiator 23 by a half round prolongation 18 of the casing 1. This protection member is

made of heat insulating material, like bakelite, or could be provided with a layer of heat insulating material. (See Fig. III.)

The operation of my invention is as follows: Steam is admitted from the radiator 23 through nozzle 2 to the chamber surrounded by the lower casing 1. When the test body 12 is dry from low humidity, valve 4 is forced down by the lever 8 and the steam passes to the interior of the lower base 1 from which it is conducted through the recesses of the upper stem 6 to the atmospheric air of the room. On account of the conical inlet and outlet of the valve stem guide 5, the discharged steam will expand in the air without any annoying noise. The test body 12 is free to move longitudinally, except as limited by adjusting screw 24 and the holding clamp 14 and 11. As the relative humidity of the air increases, the test body 13 absorbs humidity and expands. Therefore, the pressure of the fulcrumed lever 8 against the valve 4 is released and the spring 21 closes the valve. For regulating the humidity of the air by the test body 12, the adjusting screw 24 with a graduation of the relative humidity is set in such position, that the graduation pointer indicates the desirable percentage of relative humidity, p. e. 40%. It is well known, that the atmospheric air in rooms with less than 40% relative humidity is destructive to human health. If the relative humidity of the air becomes lower than the relative humidity shown by the graduation on the top of the screw 24, the valve will be opened and steam released. The valve will be closed automatically, when the desired humidity of the air in the room is obtained. The thin strips of leather allow a very quick action of the controlling device. It is obvious that any suitable hygroscopic material may be employed for the test body.

During the operation of the radiator system, it is well known that under certain conditions air is trapped in the coils and must be drained therefrom before the steam will fill the coils. Therefore the valve 4 should be independent of the humidity control 12 before the steam will fill the radiator. This is accomplished by constructing the valve 4 from a thermo-sensitive material, p. e. rubber, which has a greater coefficient of expansion than the surrounding casing 1. In cold condition the valve will decrease its length, and held by its shoulder 3 in the recess 22, it will be unable to close the outlet or to be influenced by variations of the test body. After dismissing the undesirable air the heat of the expanding steam will increase the length of the valve and it becomes under control of the test body. From the foregoing it will be readily understood that the valve 4 of the humidifying device has at the same time the function of an automatic air valve for steam radiators.

The valve stem guide 6 is provided with radial channels for discharging water to the outer surface of the external casing and the plates 27 and 28. This improvement will be preferably employed for hot water radiators. The discharged water will vaporize on the plate 27 and increase the humidity of the air. The water outlet will be controlled by the test body 12 which closes the valve, when the desired humidity is obtained. For rapid evaporation the discharged water will drop on an electro-heated container 28. The heating elements of this electric vaporizer are controlled in dependence upon the test body 12. If the desired humidity is obtained, the valve will close the water supply and the electric circuit of the electric heating elements 28 will be broken by the disconnection of the contact points 20 with the prolongation 19 of the lever 8. To prevent discharging of excess water, which may fill the container 28 to an undesirable point, there will be provided a float type air vent, to check the water outlet of the radiator. The circuit may be closed through double conductor leads or any suitable mechanism. The advantage of this arrangement is the disconnection of the electric heated system or evaporizer at the same time of discontinuance of the water supply. In addition I aim to use this electric device as a means to control, within predetermined limits of humidity changes, signals, relays or other auxiliary devices for which a need may any time arise. It is understood that any kind of water supply may be used. It will be sometimes desirable to keep the humidifying device or the control mechanism at a certain distance from the radiator or other water supply.

Although I have shown certain features of my invention for the purpose of illustration, it will be apparent that various changes may be made therein without departing from the spirit of the invention and I do not wish to be restricted to the specific embodiments shown and described except as limited thereby to the appended claims.

I claim:

1. A humidifier for radiators comprising an external casing, a valve, means for controlling the valve in dependency upon the humidity of the atmospheric air, a valve stem guide, said guide having a conical inlet and outlet opening for complete expansion of the discharged steam.
2. In a humidifier the combination of a radiator, an external casing connected with the radiator, valve means for discharging water from the radiator, said valve being controlled by a hygroscopic testbody supported by the external casing, means for evaporating the discharged water, said means consisting of a container connected with the external casing, said container being electrically heated.

3. An automatically controlled humidifier, comprising a casing adapted to be connected with a heating radiator, a valve and a hygrostat supported by the casing, the valve being connected to the radiator and controlled by the hygrostat so as to vent a portion of the heating medium from the radiator to humidify the surrounding air, said hygrostat being protected from the heat of the radiator by means of the supporting casing.

4. A humidifier comprising in combination, a radiator, an external casing connected with the radiator, a hygrostat, a valve controlled by the hygrostat, said hygrostat being protected from the heat of the radiator by means of a heat insulating material.

5. A humidifier comprising in combination, a radiator, an external casing connected with the radiator, a hygrostat, a valve controlled by the hygrostat, said valve consisting of a thermo-sensitive material so as to vent the air from the radiator.

6. A humidifier comprising in combination, a radiator, an external casing connected with the radiator, a hygrostat, a valve controlled by the hygrostat, said valve consisting of a thermo-sensitive material so as to vent the air from the radiator and means for holding said valve in an opened position.

30 7. A humidifier comprising in combination, a radiator, an external casing connected with the radiator, a hygrostat, a valve controlled by the hygrostat, said valve consisting of a thermo-sensitive material so as to vent the air from the radiator, and means for holding the valve in opened position, said means consisting of a shoulder and a recess arranged in the lower part of the casing, and spring means, adapted to keep the valve, after releasing the air from the radiator, under control of the hygrostat.

45 8. A humidifier comprising in combination, a radiator, an external casing, connected with the radiator, a hygrostat, a valve controlled by the hygrostat, said valve consisting of a thermo-sensitive material, said hygrostat comprising a plurality of thin strips of hygroscopical material and plates placed between the upper and lower end of the hygroscopic strips to increase the sensitivity of the hygrostat.

55 9. A humidifier comprising in combination a radiator, an external casing connected with the radiator, a hygrostat, a valve controlled by the hygrostat, said valve consisting of a thermo-sensitive material, said hygrostat having an adjusting screw with a graduation, to adjust the desirable humidity.

60 10. In a humidifier, the combination of a water supply system, an external casing connected with said water supply system, a valve for discharging water, said valve being controlled by a hygrostat, means for evaporating the discharged water, said means consist-

ing of a heated container connected with the external casing.

11. An automatically controlled humidifier comprising a casing adapted to be connected with a water supply system, a valve and a hygrostat supported by the casing, an electrically heated container, connected with said casing for evaporating the discharged water and means for controlling the heating medium.

15 12. An automatically controlled humidifier comprising a casing adapted to be connected with a water supply system, a water discharging valve, an electrically heated container connected with said casing and means for controlling the heating medium, said means consisting of a hygrostat.

20 13. In a humidifier, the combination of a water supply system, a casing with a valve for discharging water, said valve being controlled by a hygrostat, means for evaporating the discharged water, said means consisting of an electrically heated container.

25 14. A humidifier comprising in combination, a radiator, an external casing connected with said radiator, a valve for discharging water, said valve being controlled by a hygrostat, means for evaporating the discharged water, said means consisting of an electrical-30
